(57) **CLAIM**

The ornamental design for the bed frame, as shown and described.

DESCRIPTION

FIG. 1 is a front elevational view of the bed frame design of my new invention;

FIG. 2 is a left side elevational view thereof;

FIG. 3 is a rear elevational view thereof, depicting in part the flat rear surfaces of the central panels of the headboard and footboard;

FIG. 4 is a right side elevational view thereof, with the left side elevational view thereof being a mirror image;

FIG. 5 is a top plan view thereof;

FIG. 6 is a bottom plan view thereof;

FIG. 7 is a cross-sectional view taken along line 7—7 of FIG. 1, depicting the entire front of the headboard;

FIG. 8 is a vertical cross-sectional view taken along line 8—8 of FIG. 5, depicting the surface contour of the front of the headboard;

FIG. 9 is a horizontal cross-sectional view taken along line 9—9 of FIG. 7, further depicting the surface contour of the front of the headboard;

FIG. 10 is a vertical cross-sectional view through the footboard along line 10—10 of FIG. 5; depicting the surface contour of the front of the footboard; and,

FIG. 11 is a horizontal cross-sectional view through the footboard along line 11—11 of FIG. 10, further depicting the surface contour of the front of the footboard.
